UNITED STATES PATENT OFFICE.

BENJAMIN N. BARTLETT, OF TACOMA, AND MYCOGOH DU VALL, OF BELLINGHAM,
WASHINGTON.

VESSEL-RAISING APPARATUS.

1,300,553.

Specification of Letters Patent. Patented Apr. 15, 1919.

Application filed August 5, 1918. Serial No. 248,424.

To all whom it may concern:

Be it known that we, BENJAMIN N. BARTLETT and MYCOGOH DU VALL, citizens of the United States, residing at Tacoma, in the county of Pierce and State of Washington, and Bellingham, in the county of Whatcom and State of Washington, respectively, have invented certain new and useful Improvements in Vessel-Raising Apparatus; and they do hereby declare the following to be a full, clear, and exact description of the invention, such as will enable others skilled in the art to which it appertains to make and use the same.

15 This invention is an improvement in ships and has particular reference to an apparatus for detecting the location of sunken vessels and raising the same.

An object of the invention is to provide 20 an improved apparatus including a buoy which remains upon the surface after a vessel has sunk in order to indicate the location thereof and which remains connected to the vessel so that a lifting or raising device may 25 be lowered and automatically connected to a hook member carried by the vessel.

Another object is the provision of an apparatus of this character which is simple in construction, easy to manufacture and apply 30 to a vessel and effective in carrying out the purpose for which it is designed.

The inventive idea involved is capable of receiving a variety of mechanical expressions one of which, for the purpose of illustrating the invention, is shown in the accompanying drawing wherein:—

Figure 1 is a fragmentary longitudinal section through a vessel showing the apparatus applied thereto and in its inoperative 40 position.

Fig. 2 is a view illustrating the position of the parts of the apparatus when the vessel has been sunk.

Fig. 3 is a fragmentary transverse section 45 through the vessel showing portions of the apparatus in elevation.

Fig. 4 is an enlarged fragmentary longitudinal section through the hook member employed in connection with the invention.

50 Referring more particularly to the drawing, the numeral 5 indicates a vessel which may be of any desired construction and mounted upon one or more of the decks of the vessel at any desired point is a vertically disposed guiding and supporting frame 6 in

which is normally mounted a buoy 7 of any desired construction and carrying a signal plate 8 upon the top thereof which may be discernible when the buoy is floating upon the surface.

60 Preferably situated below the deck upon which the frame 6 is mounted, is a casing 9 in which is rotatably mounted a drum 10 having a cable 11 wound thereon and connected at 12 to the buoy 7. By reason of 65 this connection with the buoy it will be apparent that when the vessel sinks and the buoy is detached from the frame 6 and remains floating upon the surface the cable 11 will be automatically unwound from the 70 drum 10 until the vessel settles upon the bottom.

The apparatus further comprises a hook member 13 having an enlargement 14 upon its shank which is adapted to be secured to 75 the deck of a vessel at a point adjacent the frame 6 and the attachment of the hook member to the vessel is reinforced by a bar 15 forming an extension of the hook and preferably projecting to the keel of the 80 vessel where the same is attached so that the hook will be sufficiently anchored to withstand the stress applied thereto when the vessel is being raised. The bill 16 of the hook member is provided therein with a longitudinally extending opening 17 through 85 which the cable 11 passes and the lower end of said opening is flared or enlarged as indicated at 18 for a purpose which will presently appear. The cable 11 is of sufficient 90 length to permit of the vessel sinking to a considerable depth before the cable is entirely unwound from the drum and attached to the end of the cable on said drum is a stop or plug 19 which will engage in the enlargement 18 of the opening 17 after the cable has been entirely unwound from the drum 10 and said stop or plug 19 will prevent detachment of the cable from the hook member and thus provide a constant connection between 100 the latter and the buoy 7.

95 The cable 11 provides a guide for attaching a hoisting element 20, preferably in the form of a large ring, which is adapted to engage with the bill of the hook member 13 when it is desired to raise the vessel but before lowering the lifting or hoisting element 20 along the cable 11 it is essential that the latter be entirely unwound from the drum 10 so that the plug or stop 19 110

will engage in the lower end of the opening 17. The ring 20 is secured to one end of a hoisting table 21, the other end of which may be wound upon a drum of a suitable windlass mechanism (not shown) by which 5 a vessel may be raised. As the hoisting ring is lowered along the cable 11 of the guide the same will eventually engage the bill 16 of the hook member 13 and by then pulling upwardly upon the cable 21 the ring 20 may 10 be caused to engage the bight 22 of the hook member whereupon the apparatus will be in position for the hoisting or raising operation. In order to insure the retention of the 15 lifting ring 20 in engagement with the hook member the latter is provided with a locking bar 23 pivoted at 24 to the shank of the hook member and extending across the space between said shank and of the bill 16 where 20 the free end of said bar engages a lug 25 on said bill so that the bar may be swung inwardly when the lifting ring is engaged therewith after which said bar will return to its normal position and thus close the 25 space between the bill and shank of the hook member.

What is claimed is:—

1. In an apparatus of the class described, the combination with a vessel; of a hook 30 member secured thereto and having a bill portion provided with a longitudinal extending opening the lower end of which is enlarged, a drum carried by the vessel, a cable normally wound upon said drum and 35 passing through said opening in the bill of the hook member, a stop secured to the end of the cable wound upon the drum and adapted to engage in the enlarged portion of said opening when the cable is entirely 40 unwound from the drum whereby to permanently maintain the cable in connection with the hook member, a buoy adapted to remain afloat when the vessel sinks and connected to the cable to unwind the same, and a

hoisting element adapted to be lowered 45 along said cable and guided thereby into engagement with the bill of said hook member to permit of the raising of the vessel.

2. In an apparatus of the class described; the combination with a vessel of a hook 50 member secured thereto and having a bill portion provided with a longitudinal extending opening the lower end of which is enlarged, a drum carried by the vessel, a cable normally wound upon said drum and 55 passing through said opening in the bill of the hook member, a stop secured to the end of the cable wound upon the drum and adapted to engage in the enlarged portion of said opening when the cable is entirely 60 unwound from the drum whereby to permanently maintain the cable in connection with the hook member, a buoy adapted to remain afloat when the vessel sinks and connected to the cable to unwind the same, a hoisting 65 element adapted to be lowered along said cable and guided thereby into engagement with the bill of said hook member to permit of the raising of the vessel, and a pivoted locking bar carried by said hook member 70 movable to permit of the engagement of said hoisting element with the bill of the hook member and then movable to a locking position to prevent detachment of said hoisting element. 75

In testimony whereof, we affix our signatures in the presence of two witnesses.
